(57) **CLAIM**

The ornamental design for an animal collar, as shown and described.

DESCRIPTION

FIG. 1 is a rear perspective view of an animal collar showing the new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a front perspective view showing the animal collar in the context it is intended to be used.

Broken lines and portions contained within broken lines are not claimed.

1 Claim, 4 Drawing Sheets
